UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

HUMIDIFIER FOR GAS-ENGINES.

1,281,124.

Specification of Letters Patent. Patented Oct. 8, 1918.

Application filed January 26, 1915. Serial No. 4,500.

To all whom it may concern:

Be it known that I, REUBEN B. BENJAMIN, a citizen of the United States, residing at Chicago, in the county of Cook and State of Illinois, have invented new and useful Improvements in Humidifiers for Gas-Engines, of which the following is a full, clear, concise, and exact description, reference being had to the accompanying drawing, forming a part of this specification.

My invention relates to humidifiers for gas engines. In internal combustion engines it has been found that the combustion is improved if moisture, in some form, is supplied to the combustion chamber. This supply of moisture also lessens the deposit of carbon and enables a lower grade of fuel to be used.

Among the objects of my invention are to provide an improved device of the character indicated which shall be simple of construction and manufacture and efficient in operation, and which can easily be applied to existing engines.

Further objects will appear from the detailed description to follow and from the appended claims.

In the drawings, in which I have illustrated one embodiment of my invention—

Figure 1 is a side elevation of the front part of an automobile, showing the engine radiator, carbureter, dash and part of the cooling system;

Fig. 2 is a section substantially on the line 2—2 of Fig. 1 showing the manner in which the humidifier is secured to the connection which forms part of the cooling system, and showing the valve for regulating the supply of moisture, and showing also the vaporizing chamber and the pipe leading therefrom to the carbureter;

Fig. 3 is a section on the line 3—3 of Fig. 2, and

Fig. 4 is a plan view of the humidifier, parts being broken away to show the pipe leading to the carbureter and the screen above the moisture inlet.

Referring now to the drawing in detail reference character 10 indicates the hood of the automobile in which is located the engine 11. Reference character 12 indicates the radiator; 13 the dash, and 14 the carbureter which is provided with any suitable controlling valve mechanism 14^a for controlling the flow of fuel between the carbureter and the engine. Reference character 15 indicates a manifold forming a part of the cool-

ing system from which conduits 16 lead to the water jackets of the various cylinders of the engine 11. 17 indicates a nipple which is in communication with the interior 60 of the radiator 12. 18 indicates a flexible tubular member connecting the manifold 15 and nipple 17 to permit the cooling water to flow therebetween. The tubular member 18 is provided in its upper side with an 65 opening 19 through which communication is afforded with the humidifier indicated in general by 20. The humidifier comprises a vaporizing chamber 21, a tubular moisture inlet 22 provided with a butter-fly valve 23 70 for regulating the supply of moisture, and a tubular member 24 extending upwardly through the bottom of the vaporizing chamber 21 and affording communication between said vaporizing chamber and the carbureter. 75 The vaporizing chamber comprises a dished portion 25 which may be of sheet metal, and a bottom portion 26 which may be secured in any suitable manner to the moisture inlet 22. The upper wall of the dished portion 80 25 is provided with a number of small openings 27 to afford an inlet for the air to the tubular member 24 which is in communication with the carbureter. A screen 28 is placed above the moisture inlet 22 to prevent the water in the tubular member 18 85 from splashing up into the vaporizing chamber.

The lower end of the moisture inlet 22 is provided with a saddle portion 29 which engages the tubular member 18 and is provided with a pair of ears 30 through which extend screws 31 for engagement with the ears 32 of a clamping band 33 whereby the device may be firmly secured in its proper place on 95 the flexible tube 18. The butter-fly valve 23 is secured on a rock shaft 34 mounted in the walls of the inlet 22, and extending rearwardly through the dash 13. A turn button 35 is secured to the end of the shaft 34, 100 by means of a set screw 36 and is provided with a flange 37 held beneath a flanged member 38 whereby the turn button is rotatably mounted on the dash 13 of the automobile. An indicator 39 may be provided to show the 105 position of the valve 23. A flexible conduit 40 leads from the tubular member 24 to the primary air inlet 41 of the carbureter.

The operation of my improved device is as follows: When the engine is running water is forced through the manifold 15, tube 18 and nipple 17 by means of any suitable

pump (not shown). At the same time the suction of the engine causes air to be drawn in to the carbureter through the openings 27, tubular member 24, and conduit 40; the 5 air, in passing through the vaporizing chamber 21, becoming more or less saturated with moisture which is supplied from the cooling system through the opening 19, moisture inlet 22, past the valve 23 and 10 through the screen 28. As previously stated, the amount of moisture supplied to the carbureter is regulated by means of the butterfly valve 23 which may be opened more or less by means of the turn button 35. Since 15 the moisture is supplied to the fuel before it passes the fuel-controlling valve 14^a, this fuel-controlling valve mechanism also has a controlling influence on the amount of moisture supplied.

20 It will be noted that the construction of the device is such that it can readily be applied to existing types of automobiles. The purpose of extending the tubular member 24 some distance upward into the vaporizing chamber 21 is to prevent any water which might find its way into the vaporizing chamber 21 from overflowing into the conduit 40 leading to the carbureter.

25 In the claims the word "moisture" is to be understood as including water in the form of vapor, steam or spray.

Having thus described my invention what I claim as new and desire to secure by Letters Patent is:—

30 1. The combination with an automobile having a dash, an internal combustion engine having a water cooling system including a radiator and a conduit leading from the engine to the radiator, of a humidifier 35 secured to said conduit, a rotary valve controlling communication between said conduit and humidifier, and a rock shaft in alignment with the axis of said valve for operating it extending rearwardly through 40 the dash.

45 2. The combination with an automobile having a dash, an internal combustion engine having a water cooling system including a radiator and a conduit leading from the engine to the radiator, of a humidifier 50 secured to said conduit, a rotary valve controlling communication between said conduit and humidifier, a rock shaft in alignment

55 with the axis of said valve for operating it extending rearwardly through the dash, and an indicator turning with said shaft.

60 3. The combination with an internal combustion engine having a water cooling system, including a radiator and a flexible conduit leading from the engine to the radiator, of a humidifier detachably secured to said conduit.

65 4. The combination with an automobile having an internal combustion engine having a water cooling system including a radiator, and a flexible substantially horizontal conduit leading from the engine to the radiator, said conduit having an opening in its upper side, of a humidifier comprising 70 a vaporizing chamber secured to said conduit having a moisture inlet in communication with said opening.

75 5. The combination with an automobile having an internal combustion engine having a water cooling system including a radiator, and a flexible substantially horizontal conduit leading from the engine to the radiator, said conduit having an opening in its upper side, of a humidifier comprising a 80 vaporizing chamber secured to said conduit having a moisture inlet in its lower wall in communication with said opening, and an air inlet above said moisture inlet, and an outlet having its orifice a substantial distance above said moisture inlet.

85 6. The combination with an automobile having an internal combustion engine having a carbureter and a water cooling system including a radiator, and a flexible substantially horizontal conduit leading from the engine to the radiator, said conduit having an opening in its upper side, of a humidifier comprising a vaporizing chamber secured to said conduit having a moisture inlet in communication with said opening, and a conduit in communication with said chamber and leading to said carbureter.

90 In witness whereof, I have hereunto subscribed my name in the presence of two witnesses.

REUBEN B. BENJAMIN.
